United States Patent [19]

Rowen

[11] Patent Number: Des. 310,349

[45] Date of Patent: ** Sep. 4, 1990

[54] **WIRELESS TRANSMITTER FOR
SELECTABLE LIGHT LEVEL CONTROL
SWITCH**

[75] Inventor: Michael J. Rowen, Center Valley, Pa.

[73] Assignee: Lutron Electronics Co., Inc.,
Coopersburg, Pa.

[**] Term: 14 Years

[21] Appl. No.: 249,465

[22] Filed: Sep. 26, 1988

[52] U.S. Cl. D13/168; D13/171

[57] **CLAIM**

The ornamental design for a wireless transmitter for
selectable light level control switch, as shown and de-
scribed.

DESCRIPTION

FIG. 1 is an isometric illustration of a wireless trans-
mitter for selectable light level control switch showing my
new design.

FIG. 2 is a top plan view thereof.

FIG. 3 is a front elevational view thereof.

FIG. 4 is a bottom plan view thereof.

FIG. 5 is a left end elevational view thereof.

FIG. 6 is a right end elevational view thereof.

FIG. 1

FIG. 2

FIG. 3

FIG. 4

FIG. 5

FIG. 6
